United States Patent Office

Des. 210,448
Patented Mar. 12, 1968

210,448

RESTAURANT

Lee V. Burns, Glendale, David A. Deane, Hollywood, and Monroe T. Leung, Los Angeles, Calif., assignors to Federal Sign and Signal Corporation, Blue Island, Ill., a corporation of New York

Filed Nov. 21, 1966, Ser. No. 4,750

Term of patent 14 years

(Cl. D13—1)

FIG. 1.

FIG. 2.

FIG. 3.

FIG. 4.

FIG. 5.

FIG. 1 is a front elevational view of a restaurant showing our new design;

FIG. 2 is a side elevational view thereof;

FIG. 3 is the opposite side elevational view thereof;

FIG. 4 is a top plan view thereof; and

FIG. 5 is a sectional view taken along line 5—5 of FIG. 1.

The rear portion of the structure not shown is substantially plain.

We claim:

The ornamental design for a restaurant, substantially as shown and described.
